PISTON FOR AIR GUNS

Charles F. Lefever, Plymouth, Mich., assignor to
 Daisy Manufacturing Company, Plymouth,
 Mich., a corporation of Michigan

Application December 19, 1938, Serial No. 246,715

5 Claims. (Cl. 124—11)

The invention relates to pistons more particularly designed for use in air guns, and it is the object of the invention to obtain a construction which facilitates and expedites manufacture of the same. In the present state of the art air guns are usually provided with an air cylinder in which the air is compressed by the movement of a piston actuated by a spring. Forward movement of the piston is arrested by an abutment 10 while the air is discharged from the cylinder through the medium of a tube projecting forward from the piston and extending through an aperture in said abutment. This tube also performs a mechanical function of impinging against the projectile to positively actuate the same, while the compressed air causes an acceleration during further movement through the gun barrel.

In the manufacture of pistons of this type it has been customary to form a metallic core member headed at one end and on which the leather washer or other packing material is sleeved. The air tube has its inner end engaging an axial recess in this core member, and is usually secured thereto by soldering. It is one of the objects of my invention to avoid this soldering operation, as well as the mechanical operation of drilling the socket in which the end of the air tube is placed. I have, therefore, designed the following construction, as illustrated in the accompanying drawing in which:

Figure 1 is a central longitudinal section through the core member and air tube of my improved piston, the packing member and piston shank being indicated in dotted lines;

Figure 2 is a perspective view of the detached elements forming the assembly of Figure 1;

Figure 3 is a view similar to Figure 1 showing a modified construction.

40 A is the core member of the piston which may be formed of round bar stock and a head or flange B is formed at the end of the core by an upsetting operation. C is the air tube which also is upset at one end to form a flanged head D. 45 These parts are then secured to each other by a sheet metal stamping E centrally apertured to engage the tube C with a recess F for receiving the head D and with a series of peripheral axially extending prongs G. The latter are adapted to 50 embrace the head flange B of the core member and to be clinched over the same, thereby securely attaching the tube to the core. To admit air into the tube a laterally opening port H is formed just beyond the point of engagement with the stamping E. The member A is also formed with a transversely extending bore I for receiving the pin by which the piston is attached to its operating shank. This shank J and also the pis-

ton packing K are shown in dotted lines in Figure 1.

The construction as above described can be manufactured at low cost inasmuch as the elements are formed by simple mechanical operations, such as stamping and upsetting. While the assembly of these elements is accomplished more expeditiously than where a soldering operation is required, the parts are also more securely attached to each other.

In the modified construction shown in Figure 3 the stamping E is dispensed with and the head portion B' of the core member A' is recessed to receive a disk L sleeved on the tube C. The peripheral portion of the disk is beveled and the annular flange B² surrounding the recess is pressed inward to engage the same.

What I claim as my invention is:

1. In a piston for air guns, a solid cylindrical core member radially outwardly flanged at its 20 forward end, an aligned air tube radially outwardly flanged at its rear end, and a coupling member surrounding said air tube and engaging the flange thereof having a clinching engagement with the flange of said core member.

2. In a piston for air guns, a solid cylindrical core member having an upset radially outwardly extending flange at its forward end, an aligned air tube having an upset radially outwardly extending flange at its rear end in contact with said core member, and a coupling member surrounding said air tube adjacent to the flange thereof having a clinching engagement with the flange of said core member.

3. In a piston for air guns, a solid cylindrical core member having a peripheral flange at its forward end, an aligned air tube having an upset flange at its rear end contacting said core member, and a coupling formed of a sheet metal stamping surrounding said air tube and clinched about the flange of said core member.

4. In a piston for air guns, a solid cylindrical core member having an upset peripheral flange at its forward end, an aligned air tube having an upset peripheral flange at its rear end in contact with said core member, and a coupling formed of a sheet metal stamping having a portion surrounding said tube and engaging the flange thereof, and a portion clinched about the flange of said core member.

5. In a piston for air guns, a cylindrical core member recessed at its forward end to form an annular flange and having a portion of smaller diameter in rear of said recessed portion, an air tube having an upset flange at its rear end, a disk surrounding said air tube and fitting within said recess, said annular flange being closed over the periphery of said disk to retain the same.

CHARLES F. LEFEVER.
